UNITED STATES PATENT OFFICE

2,579,440

ELECTROSTATIC PRECIPITATOR

Robert T. Palmer, Sharon, Mass., assignor to
Westinghouse Electric Corporation, East Pitts-
burgh, Pa., a corporation of Pennsylvania

Application May 1, 1947, Serial No. 745,314

26 Claims. (Cl. 183—7)

1

This invention relates to electrostatic precipi-
tators for the removal of small particles such as
dust, from gases such as air.

The most successful electrostatic precipitators
for the cleaning of air, have ionization chambers
in which the foreign particles entrained in the air,
are given electrostatic charges, and have collec-
tion chambers in which the charged particles de-
posit upon oppositely charged, metal plates.
After a period of use, it is necessary to clean such
plates, which usually are cleaned by washing
down with liquids such as water.

This invention provides an electrostatic pre-
cipitator in which a dielectric sheet is given an
electrostatic charge and is moved, preferably in
a plurality of passes, through the collection cham-
ber of the precipitator, and serves as the elec-
trodes to which the charged, foreign particles are
attracted, and to which they adhere.

In one embodiment of the invention, the di-
electric sheet is unwound from a first roll at one
end of the collection chamber, and is wound up on
a second roll at the other end of the collection
chamber. When the first roll is used up, it is
replaced, and the second roll is removed and dis-
posed of, or cleaned.

In another embodiment of the invention, the
dielectric sheet is endless and is recirculated
through the precipitator, it being cleaned as by
a suction nozzle, at a point in its travel.

In one embodiment of the invention, the di-
electric sheet is electrostatically charged to one
polarity, and is passed between metal plates
charged to the opposite polarity, whereby the
charged foreign particles are repelled by the
plates towards the sheet.

In another embodiment of the invention, the
two sets of electrodes in the collection chamber
are formed by rows of dielectric sheets, alternate
sheets being given opposite electrostatic charges
whereby the charged foreign particles are re-
pelled by the sheets having the same polarity,
and are attracted to the sheets having the oppo-
site polarity.

An object of the invention is to facilitate the
removal of the foreign particles collected in an
electrostatic precipitator.

Another object of the invention is to provide
an electrostatic precipitator for the removal of
foreign particles from gases, in which the dust
attracting electrodes are electrostatically
charged, dielectric sheets movable therethrough.

Another object of the invention is to apply an
electrostatic charge to a dielectric sheet, and then
to use the sheet in an electrostatic precipitator

2

as an electrode for attracting foreign particles
entrained in a gas passed therethrough.

Another object of the invention is to apply
electrostatic charges to foreign particles en-
trained in a gas; to apply an electrostatic charge
having the opposite polarity to a dielectric sheet,
and to use the sheet for attracting the charged
particles.

Another object of the invention is to pass an
electrostatically charged, dielectric sheet in a
plurality of passes, as dust attracting electrodes,
through the collection chamber of an electro-
static precipitator.

The invention will now be described with ref-
erence to the drawing, of which:

Fig. 1 is a plan view, in section, of an electro-
static precipitator embodying this invention, the
section being taken along the lines 1—1 of Fig. 2;

Fig. 2 is a sectional view along the lines 2—2
of Fig. 1;

Fig. 3 is an enlarged, fractional view of the
lower end of one of the rollers of Figs. 1 and 2,
and of the bearing for same, the bearing being
shown in section;

Fig. 4 is a plan view, in section, of another
electrostatic precipitator embodying this inven-
tion, the section being taken along the lines 4—4
of Fig. 5;

Fig. 5 is a sectional view along the lines 5—5
of Fig. 4;

Fig. 6 is a plan view, in section, of another
electrostatic precipitator embodying this inven-
tion, the section being taken along the lines 6—6
of Fig. 7;

Fig. 7 is a sectional view along the lines 7—7
of Fig. 6;

Fig. 8 is a sectional view along the lines 8—8
of Fig. 7;

Fig. 9 is a plan view, in section, of another elec-
trostatic precipitator embodying this invention,
the section being taken along the lines 9—9 of
Fig. 10, and

Fig. 10 is a sectional view along the lines 10—10
of Fig. 9.

Referring first to Figs. 1, 2 and 3, the precipi-
tator there illustrated, includes the metal casing
10 having a gas inlet 11 in its upper wall, and a
gas outlet 12 in its lower wall. Within the cas-
ing 10 adjacent the inlet, is the ionizer chamber
13 comprising the ionizer wires 14 supported by
the framework 15 from the insulators 16, which
in turn, are attached to opposite walls of the cas-
ing. The tubular ionizer electrodes 17 are ar-
ranged on opposite sides of the wires 14 and are
supported directly from the casing walls. The

wires 14 are adapted to be connected to, for example, the +12,000 volt terminal of the direct current, power supply source 26, the casing 10 being grounded and connected to the negative terminal of the source. This construction is conventional and is illustrated by the E. H. R. Pegg Patent No. 2,181,147.

The collection chamber 18 is located between the ionizer chamber 13 and the outlet 12, and contains the vertically arranged, spaced, metal collector plates 19 which are supported in spaced slots in the metal bars 20 which are attached to opposite casing walls. The plates 19 are grounded to the casing 10 through the bars 20.

On opposite sides of the collection chamber are arranged the rollers 23 of electric insulating material, the rollers on one side having their shafts 21 in alignment with alternate of the plates 19, the rollers on the other side of the collection chamber having their shafts 21 in alignment with the others of the plates. The shafts 21 are journalled in the ball bearings 22 attached to upper and lower walls of the casing 10.

To one side of the collection chamber 18, the left-hand side, facing Figs. 1 and 2 of the drawing, and of the rollers 23 on that side, are supported the paper rolls 24 and 25, the roll 24 being a supply roll, and the roll 25 being formed by rolling up the paper supplied by the roll 24.

The paper from the roll 24 is passed over the idler roller 24, and is then passed over the rollers 23 so that it is arranged in a plurality of passes on the opposite sides of the plates 19 as the sheet electrodes 37, as illustrated by Fig. 1, and passes out the collection chamber, and after contacting the idler roller 27 is rolled up on the roll 25.

The shaft 28 of the roll 25 is supported at its lower end in the bearing 29, and its upper end is connected through the conventional speed reducing gear box 30, to the electric driving motor 31. The motor 31 is geared down through the box 30 to rotate the roll 25 at a very slow speed whereby the sheet from the roll 24 is moved at low speed through the collection chamber 18.

The sheet on leaving the idler roller 26 passes between the ionizer electrodes 34 and 35. The electrode 34 is a tubular, metal segment having a relatively large radius of curvature, and which extends the width of the sheet from the roll 24, and which is connected to, for example, the +6,000 volt terminal of the said power supply source. The electrode 34 is supported by the tubular insulators 36 from the inner casing wall 38. The electrode 35 is a comb type electrode extending the width of the sheet, having a plurality of sharp points adjacent the surface of the sheet, and is connected to the casing 10 so as to be grounded thereto.

In operation, following the energization of the direct current, power supply source, and of the motor 31, a gas to be cleaned, such as air, is drawn into the inlet 11 as by the action of a fan which is not illustrated, connected to the outlet 12. The foreign particles entrained in the gas are given positive electrostatic charges as they pass through the ionization chamber, in a process which is well known to those skilled in the art.

As the paper sheet passes between the ionizer electrodes 34 and 35 it is given a minus electrostatic charge. This sheet charging action is disclosed in detail in the Van de Graaf Patent No. 1,991,236; the Trump Patent No. 2,252,668, and in the Delcau Patent No. 2,398,581, which patents may be referred to for an understanding of the

principles involved. The charged sheet as it passes through the collection chamber acts as a set of negatively charged electrodes 37 facing the grounded plates 19 which are positive with respect to the electrodes 37. Electrostatic fields are therefore set up between the electrodes 19 and 37 which cause the positively charged, foreign particles in the gas passing through the collection chamber, to be attracted to, and to adhere to the sheet.

The charged sheet may be moved by the motor 31 through the collection chamber, continuously at a low speed, or intermittently. The size of the sheet, its length in the collection chamber, its speed of movement therethrough, etc., can be so correlated that the last pass of the sheet in the collection chamber, the lowermost sheet electrode 37 of Fig. 1, is sufficiently dirty under normal conditions as to prevent its further use as a collector electrode.

In the embodiment of the invention illustrated by Figs. 1 and 2, the precipitator can be shut down and the motor 31 stopped as the sheet on the supply roll 24 is unrolled to a minimum point. The sheet can then be cut adjacent the rolls 24 and 25 and new rolls inserted. The end of the sheet adjacent the new roll 25 would then be attached to the roll, and the end of the sheet adjacent the new roll 24 would be spliced to the outer end of the sheet on same, as is done in paper and cloth production plants. The old roll 25 would then be discarded or cleansed for reuse.

The roll 24 can be provided with a motor and gear box similar to the motor 31 and gear box 30 and adapted to rotate the roll 24 for winding up the dielectric sheet thereon. Then in case conditions are such that the last pass of the sheet through the collection chamber remains relatively clean, when the roll 24 is unwound to a minimum point, the drive for the roll 25 can be disengaged, and the drive for the roll 24 can be engaged for passing the sheet in the reverse direction to that described, through the collection chamber. When this is done the electrode 34 would be deenergized, and the similar electrode 34' would be energized for electrostatically charging the sheet.

While for the purpose of illustration, paper has been described as being used for the electrostatically charged sheet electrodes, other dielectric materials such, for example, as silk, rubber rayon or nylon could be used. Preferably the sheet used should have a very low electrical conductivity so that it can easily take on and hold electrostatic charges. The sheet could be treated with a chemical such, for example, as chlorinated diphenyl which will improve its dielectric characteristics, and which will render it fireproof.

More than one set of the electrodes 34 and 35 could be used whereby the sheet could be electrostatically charged at a plurality of spaced points, if that is necessary for adequately charging the sheet, or for maintaining it adequately charged throughout its passage through the collection chamber.

The embodiment of the invention illustrated by Figs. 4 and 5 is similar to that described in the foregoing in connection with Figs. 1-3, but differs therefrom in that the metal, plate electrodes are not used in the collection chamber, alternate of the sheet electrodes being given opposite electrostatic charges. Corresponding parts of Figs. 4 and 5 and of Figs. 1 and 2 have therefore, been given the same reference characters.

Referring now to Figs. 4 and 5, the ionizer

electrodes 44 and 45 are arranged on opposite sides of alternate passes of the sheet through the collection chamber, and the ionizer electrodes 46 and 47 are arranged on the opposite sides of the other passes of the sheet through the collection chamber. The pointed electrodes 45 are connected together and are grounded to the casing 10. The tubular segment electrodes 44 are connected together and to the +6,000 volt terminal of the power supply source. The pointed electrodes 46 are connected together and to the +6,000 volt terminal of the supply source. The tubular segment electrodes 47 are connected together and are grounded to the casing 10. With this arrangement of ionizer electrodes, the passes of the sheet moving between the electrodes 44 and 45 are given negative electrostatic charges, and are identified on Fig. 4 of the drawing, as the negatively charged, collector electrodes 48. The passes of the sheet moving between the ionizer electrodes 46 and 47 are given positive electrostatic charges, and are identified on Fig. 4 of the drawing, as the positively charged electrodes 49.

The grounded wipers 50 of flexible metal contact the sheet adjacent the electrodes 45 and 47 before it passes therebetween, and serves to remove the positive electrostatic charge from the sheet before the application of the negative electrostatic charges. The operation of the precipitator of Figs. 4 and 5 otherwise is the same as that of Figs. 1 and 2.

An advantage of the precipitator of Figs. 4 and 5 is that both sets of collector electrodes are continuously renewed. In prior precipitators using positively charged and grounded, metal plate, collector electrodes, it was found that some foreign particles were given negative charges in the ionization chamber and were deposited upon the positively charged collector plates. While the quantity of dust which collects upon the positively charged, collector electrodes is small compared to that which collects upon the negatively charged ones, it is desirable for some duties to be able to continuously renew both sets of collector electrodes.

The embodiment of the invention illustrated by Figs. 6, 7 and 8, is similar to that described in the foregoing in connection with Figs. 1 and 2 except that instead of the sheet forming the negatively charged, collector electrodes being unrolled from one roll, and rolled up on another roll, the sheet is an endless sheet, and is cleaned by suction at a point in its travel as it is recirculated through the precipitator casing. Corresponding reference characters are applied to similar parts in the precipitators of both embodiments.

Referring now to Figs. 6, 7 and 8, the endless sheet 60 is threaded over the direction changing rollers 61 and 62 located in the casing 10 to one side of the collection chamber 18, and over the rollers 23 which are similar to the rollers 23 of Figs. 1 and 2. The roller 61 has a pulley attached thereto and which is rotated through the belt 63 by the electric motor 64. The sheet is spaced, in the collection chamber, between the metal plate electrodes 19, so as to form negatively charged electrodes 37 as previously described in connection with Figs. 1 and 2.

The suction nozzle 65 is in contact with the sheet 60 on both sides thereof, and is connected at one side of the sheet to the duct 66 and at the other side of the sheet to the duct 67, the ducts 66 and 67 being connected by the duct 68 to the inlet of the blower 69 driven by the elec-

tric motor 70. The outlet of the blower 69 is connected to the outlet duct 71 which conveys the foreign particles collected from the sheet 60, to an external disposal point.

5 In operation, the sheet 60 is electrostatically charged by the electrodes 34 and 35, so as to act to attract the oppositely charged foreign particles entrained in the gas passing through the precipitator, as described in the foregoing. 10 The dust attracted to the sheet, and adhering thereto, is removed by the nozzle 65. It is preferred that the sheet 60 be, during the cleaning cycle, continuously moved at slow speed through the collector whereby the nozzle 65 will continuously remove the foreign particles adhering thereto.

15 The sheet of Figs. 4 and 5 could, of course, be made endless as in Figs. 6, 7 and 8, and recirculated through a suction nozzle whereby the sheet is continuously cleaned.

20 By using an endless electrostatically charged sheet, the necessity for replacement of the rolls such as are used in Figs. 1-5, is eliminated, and the use of a higher quality, more expensive sheet, such as silk, is therefore, justified.

25 The embodiment of the invention illustrated by Figs. 9 and 10 is similar to that described in the foregoing in connection with Figs. 1 and 2, except that a wind-up roll is not used following the last pass of the dielectric sheet through the collection chamber. Instead, the sheet is passed between the rolls 80 and 81, the roll 81 being rotated through the belt 82 by the electric motor 83. The sheet after passing between the rolls 80 and 81, coils up in the box 84 from which it can be removed for disposal when the sheet is unwound from the roll 24 to a minimum point. In this embodiment of the invention, the gas flow through the ionizer and collector chambers, is horizontal.

30 35 40 While a single dielectric sheet has been illustrated as passing in a plurality of passes through the collection chamber of each embodiment of the invention, each pass of the sheet through a collection chamber, may be considered as a separate sheet, and the plurality of passes of the sheet through a collection chamber, may be considered as a plurality of sheets.

45 50 55 While embodiments of the invention have been described for the purpose of illustration, it should be understood that the invention is not limited to the exact apparatus and arrangements of apparatus illustrated, as modifications thereof may be suggested by those skilled in the art without departure from the essence of the invention.

What is claimed is:

1. An electrostatic precipitator comprising a casing having a gas inlet and a gas outlet, and having a collection chamber between said inlet and outlet, a collector electrode in said chamber, means for charging said electrode to one polarity, a dielectric sheet, means for moving said sheet through said chamber adjacent said electrode, and means including ionizer electrodes on opposite sides of said sheet for applying an electrostatic charge to said sheet having a polarity opposite to that of said electrode.

2. An electrostatic precipitator comprising a casing having a gas inlet and a gas outlet, and having a collection chamber between said inlet and outlet, a plurality of spaced collector electrodes in said chamber, means for charging said electrodes to one polarity, a dielectric sheet, means for moving said sheet through said chamber between said electrodes, and means including ionizer electrodes on opposite sides of said sheet

for applying an electrostatic charge to said sheet having a polarity opposite to that of said electrodes.

3. An electrostatic precipitator as claimed in claim 2 in which the sheet is moved through the collection chamber in a plurality of passes between and along opposite sides of the electrodes.

4. An electrostatic precipitator comprising a casing having a gas inlet and a gas outlet, and having a collection chamber between said inlet and outlet, a dielectric sheet, means for moving said sheet in a plurality of passes through said chamber, and means including ionizer electrodes on the opposite sides of said sheet for applying electrostatic charges of one polarity to alternate passes of said sheet, and for applying electrostatic charges of the opposite polarity to the other passes of said sheet.

5. An electrostatic precipitator comprising a casing having a gas inlet and a gas outlet, an ionizer chamber between said inlet and outlet, a collection chamber between said ionizer chamber and said outlet, means in said ionizer chamber for applying an electrostatic charge of one polarity to the foreign particles in the gas passing therethrough, a dielectric sheet, means for moving said sheet through said collection chamber, and means including ionizer electrodes on opposite sides of said sheet for applying an electrostatic charge to said sheet having a polarity opposite to that of said particles.

6. An electrostatic precipitator as claimed in claim 5 in which the sheet is moved in a plurality of passes through the collection chamber.

7. An electrostatic precipitator comprising a casing having a gas inlet and a gas outlet, an ionizer chamber between said inlet and outlet, a collection chamber between said ionizer chamber and said outlet, means in said ionizer chamber for applying an electrostatic charge having one polarity to the foreign particles in the gas passing therethrough, a dielectric sheet, means for moving said sheet in a plurality of passes through said collection chamber, and means including ionizer electrodes on the opposite sides of said sheet for applying an electrostatic charge having the same polarity as said particles to alternate passes of said sheet, and for applying an electrostatic charge having the opposite polarity to the other passes of said sheet.

8. An electrostatic precipitator comprising a casing having a gas inlet and a gas outlet, an ionizer chamber between said inlet and outlet, a collection chamber between said ionizer chamber and said outlet, means in said ionizer chamber for applying an electrostatic charge having one polarity to the foreign particles in the gas passing therethrough, a plurality of collector electrodes in said collection chamber, means for applying an electric charge to said electrodes having the same polarity as said particles, a dielectric sheet, means for moving said sheet in a plurality of passes between said electrodes, and means for applying an electrostatic charge to said sheet having the opposite polarity to said electrodes.

9. An electrostatic precipitator comprising a casing having a gas inlet and a gas outlet, a collection chamber between said inlet and outlet, a supply roll having a dielectric sheet wound thereon at one end of said chamber, sheet moving means at the other end of said chamber, means for passing sheet from said supply roll through said collection chamber to said sheet moving means, and means including ionizer electrodes on the opposite sides of said sheet for

applying an electrostatic charge to said sheet when it enters said chamber.

10. An electrostatic precipitator as claimed in claim 9 in which the sheet is arranged in a plurality of passes in the collection chamber.

11. An electrostatic precipitator comprising a casing having a gas inlet and a gas outlet, a collection chamber between said inlet and outlet, a plurality of spaced, collector electrodes in said chamber, means for electrically charging said electrodes to one polarity, a supply roll having a dielectric sheet wound thereon at one end of said chamber, sheet moving means at the other end of said chamber, means for passing sheet from said supply roll in a plurality of passes between said electrodes, to said sheet moving means, and means including ionizer electrodes on the opposite sides of said sheet for applying an electrostatic charge to said sheet, opposite in polarity to that of said electrodes.

12. An electrostatic precipitator comprising a casing having a gas inlet and a gas outlet, an ionization chamber between said inlet and outlet, a collection chamber between said ionization chamber and said outlet, means in said ionization chamber for applying an electrostatic charge of one polarity to the foreign particles in the gas passing therethrough, a plurality of spaced, collector electrodes in said collector chamber, means for electrically charging said electrodes to the same polarity as said particles, a supply roll having a dielectric sheet wound thereon at one end of said chamber, sheet moving means at the other end of said chamber, means for passing sheet from said supply roll in a plurality of passes between said electrodes to said sheet moving means, and means for applying an electrostatic charge to said sheet opposite in polarity to that of said electrodes.

13. An electrostatic precipitator comprising a casing having a gas inlet and a gas outlet, a collection chamber between said inlet and outlet, an endless dielectric sheet, means supporting said sheet in a plurality of passes in said chamber, means for rotating said sheet, and means including ionizer electrodes on the opposite sides of said sheet for applying an electrostatic charge to said sheet to said sheet.

14. An electrostatic precipitator as claimed in claim 13 in which means is provided for continuously cleaning the sheet during the rotation thereof.

15. An electrostatic precipitator as claimed in claim 13 in which means including a suction nozzle is provided for continuously cleaning the sheet during the rotation thereof.

16. An electrostatic precipitator comprising a casing having a gas inlet and a gas outlet, a collection chamber between said inlet and outlet, a plurality of spaced collector electrodes in said chamber, means for electrically charging said electrodes to one polarity, an endless, dielectric sheet, means supporting said sheet in a plurality of passes between said electrodes, means for rotating said sheet, and means including ionizer electrodes on the opposite sides of said sheet for applying an electrostatic charge to said sheet opposite in polarity to that of said electrodes.

17. An electrostatic precipitator as claimed in claim 16 in which means is provided for continuously cleaning the sheet during the rotation thereof.

18. An electrostatic precipitator as claimed in claim 16 in which means including a suction nozzle

zle is provided for continuously cleaning the sheet during the rotation thereof.

19. An electrostatic precipitator comprising a casing having a gas inlet and a gas outlet, an ionizer chamber between said inlet and outlet, a collection chamber between said ionizer chamber and said outlet, means in said ionizer chamber for applying an electrostatic charge of one polarity to the foreign particles in the gas passing therethrough, an endless dielectric sheet, means for supporting said sheet in a plurality of passes in said collection chamber, means for rotating said sheet, and means including ionizer electrodes on the opposite sides of said sheet for applying an electrostatic charge to said sheet opposite in polarity to said particles.

20. An electrostatic precipitator as claimed in claim 19 in which means is provided for continuously cleaning the sheet during the rotation thereof.

21. An electrostatic precipitator as claimed in claim 19 in which means including a suction nozzle is provided for continuously cleaning the sheet during the rotation thereof.

22. An electrostatic precipitator comprising a casing having a gas inlet and a gas outlet, an ionizer chamber between said inlet and outlet, a collection chamber between said ionizer chamber and said outlet, means in said ionizer chamber for applying an electrostatic charge of one polarity to the foreign particles in the gas passing therethrough, a plurality of spaced, collector electrodes in said collection chamber, means for applying an electric charge to said electrodes having the same polarity as said particles, an endless, dielectric sheet, means for supporting said sheet in a plurality of passes between said electrodes, means for rotating said sheet, and means including ionizer electrodes on the opposite sides of said sheet for applying an electrostatic charge to said sheet opposite in polarity to said electrodes.

23. An electrostatic precipitator as claimed in claim 22 in which means is provided for continuously cleaning the sheet during the rotation thereof. 45

24. An electrostatic precipitator as claimed in claim 22 in which means including a suction nozzle is provided for continuously cleaning the sheet during the rotation thereof.

5 25. An electrostatic precipitator comprising a casing having a gas inlet and a gas outlet, and having a collector chamber between said inlet and outlet, a dielectric sheet, means for moving said sheet through said chamber, and means 10 including ionizer electrodes on the opposite sides of said sheet for applying an electrostatic charge to said sheet by providing an excess of ions having the same polarity thereon.

15 26. An electrostatic precipitator comprising a casing having a gas inlet and a gas outlet, and having a collector chamber between said inlet and outlet, a dielectric sheet, means for supporting said sheet for movement in a plurality of passes through said chamber, means for moving 20 said sheet, and means including ionizer electrodes on the opposite sides of said sheet for applying an electrostatic charge to said sheet by providing an excess of ions having the same polarity thereon.
